UNITED STATES PATENT OFFICE.

EVELYN M. WESTHAVER, OF SAN DIEGO, CALIFORNIA.

EMBROIDERY-HOOP.

1,221,123.

Specification of Letters Patent.

Patented Apr. 3, 1917.

Application filed June 15, 1916. Serial No. 103,777.

To all whom it may concern:

Be it known that I, EVELYN M. WESTHAVER, a citizen of the United States, residing at San Diego, in the county of San Diego and State of California, have invented certain new and useful Improvements in Embroidery-Hoops, of which the following is a specification.

My invention relates to a hoop to be used for stretching and holding material for needle work and the like, more particularly for embroidery work, and the objects of my invention are: first, to provide a hoop of this class in which one of the members is elastic throughout its full length and is required to be stretched over the other member which is non-elastic, thus providing a tight fit over the whole periphery of the hoop; second, to provide such an elastic member consisting of a plurality of pieces of rubber so that a portion will not stretch so as to have weak places in the hoop; third, to provide a hoop of this class in which the elastic member fits snugly in a concave groove in the other member so that it will hold very light material as well as heavy material; fourth, to provide means for readily mounting the elastic member in position on the other hoop member and for removing the same; fifth, to provide a hoop of this class in which the elastic member is provided with a soft covering so that very fine or delicate material will not be injured in its use, and sixth, to provide a device of this class which is simple and economical of construction, durable, easy to operate and will not readily deteriorate or get out of order.

With these and other objects in view as will appear hereinafter my invention consists of certain novel features of construction, combination and arrangement of parts as will be hereinafter described in detail and particularly set forth in the appended claim, reference being had to the accompanying drawings and to the characters of reference thereon which form a part of this specification, in which:

Figure 1 is a perspective view of my hoop complete. Fig. 2 is a perspective view of a fragmentary portion of the non-elastic member of my hoop. Fig. 3 is a perspective view of the elastic element of my hoop. Fig. 4 is a sectional view through A—B of Fig. 1. Fig. 5 is a sectional view through C—D of Fig. 3, and Fig. 6 is a longitudinal

sectional view of a fragmentary portion of the elastic member at the joint.

Similar characters of reference refer to similar parts throughout the several views.

The rigid member 1, elastic members 2, 60 covering 3, connection 4, connection covering 5 and rings 6 constitute the principal parts of my embroidery hoop.

The hoop 1 is of circular form and sufficiently rigid to retain its position and its 65 outer surface is concave and its inner surface convex forming a concave groove into which fits snugly the elastic member which consists of the covering 3 and a plurality of rubber bands 2. These rubber bands and 70 covering are secured together at their ends by means of the connection 4 which is a metallic piece with the ends swaged inwardly against the covering 3 and inside these swaged ends are the rings 6 which fit 75 tightly around the ends of the rubber bands 2 for connecting them together. Over this metallic piece 4 and secured to the covering 3 is a covering 5 which is provided with extended ends 5^a adapted for a hand hold for 80 placing the elastic portion of the hoop in the groove and for removing the same.

Though I have shown and described a particular construction, combination and arrangement of parts I do not wish to be limited to this particular construction, combination and arrangement but desire to include in the purview of my invention the construction, combination and arrangement substantially as set forth in the appended 90 claim.

It is obvious that with this construction there is provided a hoop to be used for embroidery and other purposes which combines a rigid hoop member with a concave 95 groove in the outer surface and an elastic member provided with an elastic covering adapted to fit snugly into the groove in said rigid hoop when stretched over the same, that the elastic element consisting of a plurality of rubber bands provides a means for making a tight fit and with proper pressure on the various portions of the hoop and provides for reserve in case some of the 100 elastic bands should become ruptured or weakened, that the covering 4 provides means to facilitate the ready placing and removing of the elastic member from the rigid hoop member, that the device as a 105 whole is simple and economical of construc- 110

tion, durable, easy to operate and will not readily deteriorate and get out of order.

Having thus described my invention what I claim as new and desire to secure by Letters Patent, is:

In a device of the class described, a rigid hoop member with a concave groove in its outer surface, an elastic member composed of a plurality of rubber bands in circular form adapted to fit snugly in the groove in said rigid hoop, an elastic fabric covering

for said rubber bands, means for connecting the ends of said rubber bands and said covering together and means for covering said connecting means provided with extended ends adapted to facilitate the removal of said elastic member from said rigid hoop member. 15

In testimony whereof, I have hereunto set my hand at San Diego, California, this 9th 20 day of June 1916.

EVELYN M. WESTHAVER.
